J. Miller.

Tool for Boring Tube-Heads, &c.

N° 61,629.

Patented Jan. 29, 1867.

United States Patent Office.

JAMES MILLER, OF NEW YORK, N. Y.

Letters Patent No. 61,629, dated January 29, 1867.

IMPROVED BORING TOOL.

The Schedule referred to in these Letters Patent and making part of the same.

TO ALL WHOM IT MAY CONCERN:

Be it known that I, JAMES MILLER, of the city, county, and State of New York, have invented a certain new and useful Improvement in Expanding or Adjustable Tools for Annular Cutting or Grooving applicable to cutting out tube heads in boiler-making and other purposes; and I do hereby declare the following to be a full, clear, and exact description of the same, reference being had to the accompanying drawing, which forms part of this specification, and in which—

Figure 1 is a longitudinal view or elevation of my improved annular cutter, as adapted to be attached to and operated by a drilling machine.

Figure 2 is a vertical section of the same, taken as denoted by the lines *z z* in figs. 3 and 4.

Figure 3 is an inverted plan of the tool; and

Figure 4 a horizontal section taken through the line *z z*, figs. 1 and 2.

Like letters refer to like parts in all the figures.

My invention relates to a tool that may be driven by an ordinary drilling machine, in which cutters are employed on opposite sides of the centre of a revolving head, either for cutting out round holes in a body or plate by annularly grooving its surface till the cutters are projected through the plate, or by not cutting through the plate, merely grooving its surface, said cutters being adjustable to regulate the pitch or diameter of the cut, and being kept up to their work by forcing down the tool thereon, or feeding the work to the latter that rests on the work by an adjustable centre; and my improvement consists, firstly, in a peculiar construction and arrangement of the cutters in adjustable slides within the revolving head, by arranging the cutting edges or front faces of the two opposite cutters in a plane or thereabouts intersecting the tool at its centre, and forming the outer sides of said cutters of a sweep not exceeding or thereabouts the sweep of the smallest circle they are designed to move in; also the inner sides of said cutters preferably being made flat to give increased facility for grinding, while the construction of the outer sides and arrangement of the front faces admit of the same cutters being used in all circles within the range of their adjustment in the head that carries them; and my improvement further consists in a combination of opposite adjustable cutters, substantially of the character herein described, with a self-adjusting raising and lowering centre or centre-pin to the head that carries the cutters; likewise in combination, with a self-adjusting centre or centre-pin, of cutters on opposite sides thereof, made separately adjustable relatively to said centre in their revolving head.

To enable others skilled in contrivances of the character to which this my improvement relates, I will now proceed to describe it with reference to the drawing.

A is the stem of the revolving cutter-head *B*. This stem is designed to fit in the spindle or stock of an ordinary drilling machine, and is made hollow to receive within it a centre-pin, *C*, that is made to press outwards by means of a spring, *a*, arranged within the stem and caused to bear on a collar of the pin, a slot, *b*, in the latter and cross-bar or stop, *c*, serving to admit of the requisite up-and-down play to the centre-pin, and to lock it when fully projected. The cutter-head *B* may be of any suitable diameter, and is fitted on opposite sides of the centre-pin, and nearly opposite to each other, with slides, *D*. These slides are provided with cutter apertures, *d e*, arranged one outside of the other on opposite sides of a stem, *f*, to either slide, to give different diameters of cut, irrespective of the adjustment of the slide, which is held steady to its way in the head *B*, by a plate, *g*, on the upper side of the latter, and wedge, *h*, passing through the stem *f* of the slide. Either slide is further provided with an adjusting screw, *k*, gearing into a female thread in the side of the slide and separately operative, that is, the one screw without the other, to admit of each slide being independently worked more or less out parallel with radial lines from the centre-pin. The cutters *S S'* are plain bars of steel of similar configuration to the apertures *d e*, in the slides through which they pass, and in which they are held by set-screws, *m* and *n*, of different length, the longer screws, *m*, serving to hold the cutters when they are arranged on the inner sides of the stems *f*, and the shortest screws, *n*, to secure them when on the outer sides of said stems. These cutters are shaped and arranged as follows: the thickest and cutting edges or front faces, *o*, of the two opposite cutters are in a plane that intersects the pin *C*, at its centre or thereabouts, their inner faces or sides, *r*, straight, and their outer faces or sides, *s*, convex, and of the same sweep or thereabouts as the sweep of the smallest circle they are designed to move in. This may be the construction of the cutters throughout their length, and at both ends, so that they may be reversed to cut from either end.

From this description, the following remarks will suffice to explain the general operation of the tool: Supposing it be desired to cut out tube heads in boiler plates, a purpose for which this tool is specially adapted, instead of drilling out the plates in the old slow and wasteful method of employing, for the purpose, a revolving ring with cutters adjusted by packing pieces, or scroll cutter with a self-adjusting centre-pin, or again, as has been proposed, a different construction of cutters, with the head that carries them worked by hand to unscrew down over the centre-pin, it is here only necessary to adjust, by the screws *k*, the cutting edges or faces *o* of the cutters *S S'* to an equal and requisite distance from the centre of the pin *C*, and after centring said pin in the plate, to steady the plate by the one hand while regulating the motion of the drilling machine by the other, or using both hands to the plate, the cutter-head, in descending over the self-adjusting centre-pin, feeding the cutters up to their work, till the annular groove is made through the plate, which forms the required hole, leaving a core to be afterwards utilized. If it be desired to cut out washers by the tool, then the slides being separately adjustable, the two cutters *S S'* are set at different distances from the centre-pin, corresponding at their cutting edges to the inner and outer circumferences of the washer, and the same operation gone through as in cutting out tube heads. Having cutter apertures on either side of the stems *f* of the slides renders the adjustment of the slides by the screws *m* or *n* less frequent and prolonged. By the construction and arrangement of the cutters *S S'* as described, that is, by the cutting edges or faces *o* of both being in a plane intersecting the pin *C*, at its centre, and giving their outer sides *s* a convex form not exceeding the smallest circle they are designed to move in, the same cutters are adapted to work in larger circles, as by such construction and arrangement the cutting edges or faces *o* will occupy the nearest and most distant points in the traverse of the cutter, or, in other words, no portion of the bodies of the cutters in the wake of the cutting edges will, on varying the diameter of circle for them to travel in, be outside or inside of the course described by the outer and inner edges of the cutting faces *o*, which would not be the case in varying the diameter of the cut were the cutting edges or faces arranged considerably in advance, on opposite sides of a plane intersecting the pin *C* at its centre, and their outer sides *s*, of a sweep larger than the one circle the cutters were constructed to travel in, and which would require different cutters for different diameters of grooves. This multiplicity of cutters, however, by the construction and arrangement I have described, is avoided, and the inner faces *r* of the cutters may be made flat, instead of a concave form, corresponding to the inner sweep of the groove, by which construction the cutters may be more readily ground from time to time and made serviceable, and repaired when broken. The revolving head *B* I propose to provide with a lubricating cup, *P*, made adjustable or else arranged to fit holes lying over the various diameters of grooves the cutters are intended to travel in, for oiling the work in the track of the cutters.

What I here claim as new and useful, and desire to secure by Letters Patent, is—

1. The combination, with adjustable slides *D*, in a cutter-head *B*, of cutters *S S'*, on opposite sides of their centre of rotation, and with their two cutting edges or faces *o* lying in a plane or thereabouts intersecting said centre, and their outer sides *s* of a sweep not exceeding, or thereabouts, the sweep of the smallest circle they are designed to travel in, constructed and arranged substantially as specified.
2. The combination of the adjustable cutters *S S'*, arranged substantially as described, with the self-adjusting centre or centre-pin *C*, and cutter-head *B*, essentially as herein set forth.

JAMES MILLER.
